UNITED STATES PATENT OFFICE.

WILLIAM FIRMAN, OF OTTUMWA, IOWA.

DRILLING-MACHINE POST.

1,015,160.

Specification of Letters Patent.

Patented Jan. 16, 1912.

Application filed October 26, 1910. Serial No. 589,209.

To all whom it may concern:

Be it known that I, WILLIAM FIRMAN, a citizen of the United States, residing at West End Ottumwa, in the county of Wapello and State of Iowa, have invented new and useful Improvements in Drilling-Machine Posts, of which the following is a specification.

This invention relates to coal and rock 10 drilling machines, to be used in mining and for drilling when sinking shafts, and it consists in the peculiar construction and combination of devices which will be more fully set forth hereinafter and particularly 15 pointed out in the claim.

With the above, and other objects in view, which will appear as the description progresses, the invention resides in the novel construction and combination of parts hereinafter fully described and claimed.

In the accompanying drawings, Figure 1 is a side elevation of a drilling machine constructed in accordance with the present invention. Fig. 2 is a top plan view of the 25 same. Fig. 3 is a sectional view taken upon the line 3—3 of Fig. 2. Fig. 4 is a vertical longitudinal sectional view taken through the supporting post.

In the accompanying drawings the number 30 1 designates the boxing of the device. This boxing 1 comprises a pair of sections 2 and 3 both hingedly connected together as at 4. The alining portions of the sections 2 and 3 are provided with interior 35 bores, each semi-cylindrical in cross section and each provided with suitable threads, the said threads being adapted for the reception of a screw shaft 5. The shaft 5 has its opposite ends reduced as at 6 and 7 to provide for the reception of a suitable bit 8. The screw shaft 5 is also provided with a longitudinally extending channel 9, the same adapted to receive a lug 10 provided upon a beveled toothed wheel 11. The section 40 3 of the boxing 1 is provided with an offset or substantially L-shaped arm 12 and the said arm is provided with a bore 13 which is arranged transversely of the bore provided by the sections 2 and 3. Mounted 45 within this bore 13 is a shaft 14, and se-

cured to the outer end of the said shaft is a suitable handle 15. The inner portion of the shaft 14 projects a slight distance beyond the offset 12, and is provided with a beveled toothed wheel 16, which meshes 55 with the toothed wheel 11.

The numeral 17 designates the post for the machine. This post 17 comprises a hollow member preferably of a circular cross sectional contour and the said member is 60 provided with a plurality of openings 18, the purpose of which will presently be set forth. The upper portion of the member 17 is provided with a collar 19, and this collar is formed with a threaded opening adapted 65 for the reception of a threaded bolt 20. The bolt 20 is adapted to engage a sliding bar 21 which has its upper extremity cone-shaped as at 22. The lower extremity of the post 17 is substantially closed except for 70 a central threaded aperture 23. The said aperture 23 is adapted for the reception of a threaded adjusting screw 24, the lower portion of the said screw being provided with an opening within which is positioned 75 a sliding handle 25. The post 17 is normally connected to the boxing 1 through the medium of a transversely arranged bolt 26 which is adapted to pass through any of the series of openings 18 of the said post 17, 80 and the said bolt securely compresses the post 17 between the section 3 and the offset 12 of the boxing through the medium of an adjusting nut 27.

From the above description, taken in connection with the accompanying drawings it will be noted that I have provided an extremely simple and effective device for the purpose intended, and while I have illustrated and described the preferred embodiment of the improvement, as it now appears to me, minor details of construction, within the scope of the following claim may be resorted to if desired.

Having thus fully described the invention, what I claim as new is:—

A drilling machine of the class set forth, comprising a boxing provided with an L-shaped offset member, a screw shaft mounted within the boxing and means for 100

rotating the screw shaft, the boxing being further provided with a longitudinally extending bolt approximately alining with the L-shaped offset, a hollow post being provided with a plurality of openings adapted to receive the bolt, a nut engaging the bolt and adapted to force the post against the boxing and the longitudinal arm of the offset

of the boxing, substantially as and for the purpose set forth. 10

In testimony whereof I affix my signature in presence of two witnesses.

WILLIAM FIRMAN.
